UNITED STATES PATENT OFFICE.

ELMER E. LANE, OF BEVERLY, MASSACHUSETTS, ASSIGNOR TO UNITED SHOE MACHINERY COMPANY, OF PATERSON, NEW JERSEY, A CORPORATION OF NEW JERSEY.

BUFFING-MACHINE.

1,078,050.

Specification of Letters Patent. Patented Nov. 11, 1913.

Application filed March 7, 1913. Serial No. 752,752.

To all whom it may concern:

Be it known that I, ELMER E. LANE, a citizen of the United States, residing at Beverly, in the county of Essex and State of Massachusetts, have invented certain Improvements in Buffing-Machines, of which the following description, in connection with the accompanying drawings, is a specification, like reference characters on the drawings indicating like parts in the several figures.

This invention relates to buffing machines and is herein illustrated in connection with a machine for buffing parts of boots and shoes. In machines of this class it has been customary to pass the stock, for example counters, box toes, etc., between a feed roll and a buffing roll which are located approximately in the mouth of a suction conduit and to provide in the rear of the rolls a brush to remove from the buffed stock the dust generated during the buffing operation. With this construction, however, the removal of dust has been incomplete since a certain amount of dust clings to the buffed surface despite the action of the brush and is therefore not in position to be swept out by the current of air. Moreover, from the fact that the brush has been arranged in proximity to the buffing roll, the current of air produced by the suction apparatus has been blocked at just the point at which it should have been permitted free passage.

In order to remedy these and other defects, one feature of the present invention consists in a machine of the class described of a striker arranged to deliver upon the buffed article a series of blows which serve to disengage the dust from the surface of the article and to raise it into position to be swept away. This striker may be placed in any suitable location and in the illustrated machine it replaces the usual cylindrical brush and comprises a hub having mounted thereon a longitudinal ridge of stiff bristles, said ridge being arranged to strike the stock once for each revolution of the hub. In this way, the dust is beaten out of the buffed surface of the stock and the obstruction to the current of air between the striker and the buffing roll is but momentary.

Another feature of the invention consists of a perforated guide arranged at an angle to deflect the stock in its passage and direct

it back toward the operator into position to be readily removed from the machine.

These and other features of the invention, including certain details of construction and combinations of parts will be set forth in connection with an illustrative machine and pointed out in the appended claims.

Referring now to the accompanying drawings,—Figure 1 is a longitudinal vertical section through a machine in which the present invention is embodied; Fig. 2 is a front elevation of the machine, and Fig. 3 is a side elevation of the machine.

The buffing roll 1, herein shown as a split roll, is fast to a shaft 3 which is rotatably mounted in slideable bearings the positions of which may be controlled by adjusting screws one of which is shown at 5. The feed roll 7 which has a facing of rubber or other yielding material is fast to a shaft 9 which is rotatable in fixed bearings. The plane which includes the axes of both rolls is inclined; and, slidably mounted upon the frame of the machine, in a plane parallel to this one, is a plate 11 which is adjustably held between the upper pair of screw bolts 13 and the lower pair of screw bolts 15 so that the position of said plate may be adjusted for a purpose presently to be described. A presser 17 which extends in a direction oblique to the direction of feed and within a short distance of the bite of the rolls is adjustably held in position on the plate 11 by screws 19 which pass through slots 21 in the presser and are threaded into the plate. The purpose of this presser is to press against the blank 100 and force a portion of it into the yielding face of the roll 7 so that the blank (particularly the thin ends thereof) may be firmly gripped during the buffing operation, this gripping action being desirable by reason of the fact that the buffing roll 1 rotates at much greater speed than the feed roll 7.

The rolls 1 and 7 are partially surrounded by the mouth of a suction conduit, said conduit being connected with a suction apparatus 27 of any approved type the movable member of which is fast to the shaft 29. This conduit is of a width slightly greater than the length of the rolls, and its upper wall is formed by a hinged portion 23 so that ready access may be had to the buffing roll.

At the rear of the rolls and approximately in the line of feed of the stock is located a shaft 31 having fast thereon the hub 33 of a striker 35 herein shown as formed of stiff bristles and consisting of a segment of a cylindrical brush. Below the striker and rolls is a perforated guide 37 arranged at an angle to deflect the piece of stock after it has passed the striker and turn it back 10 toward the front of the machine in position to be removed readily. This guide has flaring wings as shown in Fig. 2 and fills the lower portion of the mouth of the dust conduit being fastened to the side walls of said 15 conduit by screws 38 which pass through ears on said guide and into said walls. The upper wall 23 of the suction conduit forms a cover which is pivoted to the frame at 37, and adjustably mounted on bosses on this 20 cover is a plate 40. A buffering roll operated at high speed carries with it in its revolution a cloud of dust a portion of which is ejected from the front of the machine. The plate 40 is adjusted as close as possible to the periphery of the roll 1 and serves to deflect this moving cloud and direct the dust into the suction conduit. It also serves by closing the space between the roll and the hinged cover to concentrate the draft. 25

Referring now to Figs. 2 and 3, the shaft 3 upon which the buffering roll is mounted carries a pulley 41 over which and over a pulley 43 on the counter-shaft 45 passes a belt 47, a belt tightener 49 operated by a handle 51 being provided for maintaining the tension on said belt. On the shaft 29 of the fan is a pulley 53, and on the shaft 31 of the striker is a pulley 55, said pulleys being driven by a belt 57 which passes around said 30 pulleys and around a pulley 59 on the counter-shaft, a belt tightener 61 operated by a handle 63 being provided around which the belt 57 also passes. From the connections indicated above it will be evident that the 35 buffering roll, the striker and the fan will all be rotated at a speed greater than that of the counter-shaft 45. In practice the buffering roll is rotated at from 3000 to 4000 revolutions per minute. 40

The feed roll is driven at comparatively low speed by the following mechanism: Fast to the counter-shaft 45 is a sprocket 61 around which and around a sprocket 63 on a shaft 65 passes a chain 67. On one 45 end of shaft 65 is a small gear 69 which meshes with a large gear 71 on one end of another shaft 73 the other end of which carries a small sprocket 75; and around the last named sprocket and a sprocket 77 on the 50 shaft 9 of the feed roll passes a chain 79. A roll 81 carried by an adjustable bracket serves to tighten this chain; and a similar roll 83, similarly mounted, serves to tighten the chain 67. 55

In the operation of the machine the plate

11 is properly adjusted and the presser 17 set with reference to the thickness of the stock so as to leave between the surface of the feed roll and the operative surface of the presser a space the width of which is 70 less than that of the stock to be buffed. Power is then applied to the counter-shaft thereby rotating the buffering roll, the striker and the fan at high speed and the feed roll at comparatively low speed. The pieces of stock are fed one by one to the machine. Each piece of stock is gripped between the presser and the yielding surface of the feed roll by being pressed into said yielding surface. The stock is thus firmly held while 75 the buffering roll rotating at high speed buffs said stock. As the forward end of the piece of stock emerges from between the rolls and approaches the shaft 31 a rapid succession of blows is delivered upon it by the striker 80 35 so that the forward portion of the stock vibrates rapidly between the position shown in full lines and that shown in dotted lines in Fig. 1. This striking of the stock serves to beat out the dust generated by the buffering 85 operation and to present the dust thus raised in position to be carried away by the suction apparatus. As the stock continues to be advanced, its forward end presently 90 encounters the inclined perforated guide 37 95 and is deflected outwardly toward the operator.

I have found the striking or tapping of the free end of the stock very effective as compared with a uniform brushing action. 100 The successive sharp blows effectively raise the dust which normally clings to the buffed surface of the stock and would not be thoroughly removed by the action of the usual cylindrical brush. I have found, however, 105 that the desirable effects of both the striker and an ordinary cylindrical brush may be secured by forming the striker as illustrated, as a segment of a cylindrical brush and using very stiff bristles which yield as a 110 whole very slightly if at all.

Although the invention has been set forth in connection with a particular machine it should be understood that the invention is not limited in the scope of its application 115 to the particular machine shown and described.

Having thus described my invention, what I claim and desire to secure by Letter Patent of the United States is:—

1. A machine of the class described having, in combination, a buffering roll, means for feeding stock to said roll, and means for vibrating the stock after it has passed said roll.

2. A machine of the class described having, in combination, a buffering member for acting upon stock, means for feeding the stock to said member, and means for removing the dust generated by the buffering oper- 130

ation, said last named means including a movable member for jarring the stock to raise the dust from its surface.

3. A machine of the class described having, in combination, means for feeding stock to said roll, and means for removing the dust generated by the buffing operation, said last named means including a member for beating the stock to raise the dust from its surface.

4. A machine of the class described having, in combination, a buffing member, means for feeding stock to said member, means for drawing a current of air past said member and feeding means, and means for beating the buffed portion of the stock to raise the dust into position to be swept away by said current.

5. A machine of the class described, having, in combination, a buffing roll, means for feeding stock to said roll, means for drawing a current of air past said roll, and means for striking the stock and brushing the dust therefrom, said last named means including a brush formed as a portion of a cylinder.

6. A machine of the class described having, in combination, a buffing roll and a feed roll between which the stock passes, a suction conduit having a mouth arranged in proximity to said rolls, and a perforated guide arranged to deflect the buffed stock and direct it back toward the front of the machine.

7. A machine of the class described hav-

ing, in combination, a buffing roll, means for rotating said buffing roll at high speed, a feed roll having a yielding surface, means for rotating said feed roll at comparatively low speed, a presser arranged to coöperate with the feed roll to grip the stock by pressing a portion of said stock progressively into said yielding surface, means for drawing a current of air past said rolls, and a striker arranged in the rear of said rolls and adapted to deliver upon the free end of the stock a rapid succession of blows.

8. A machine of the class described having, in combination, a buffing roll and a feed roll between which the stock passes, a suction conduit the mouth of which embraces said rolls, and a deflector extending from one wall of said conduit into close proximity to one of said rolls.

9. A machine of the class described having, in combination, a buffing roll and a feed roll between which the stock passes, a suction conduit the mouth of which embraces said rolls, one wall of said conduit being movable to permit access to said buffing roll, and an adjustable deflector carried by said movable wall and extending into close proximity to said buffing roll.

In testimony whereof I have signed my name to this specification in the presence of two subscribing witnesses.
